METHOD FOR PROCESSING PLASTIC SHEETS

Sheldon Gordon, Madison, Wis., assignor, by
mesne assignments, to the United States of
America as represented by the Secretary of War

Application December 10, 1945, Serial No. 634,044

2 Claims. (Cl. 18-48)

1

This invention relates to the rolling of plastic materials and, more particularly, to a method of rupturing bubbles formed during rolling of hazardous plastic compositions.

In the manufacture of smokeless powder, differential rolling is frequently used to form colloided sheets from mixtures such as those containing nitrocellulose and nitroglycerin. The mixture is dumped onto horizontally disposed heated differential rolls as a wet paste and rolled to bring about the formation of a colloided sheet on the faster roll. During this hazardous process, protruding bubbles of steam are formed between the sheet and the faster roll as the moisture in the charge is rapidly dissipated by the heated roll in combination with the heat generated by the rolling operation.

The formation of these bubbles presents a considerable fire hazard in the rolling of smokeless powder. The compression of the bubbles as they pass into the bite of the rolls causes them to burst and a fire frequently results. The theory has been advanced that escaping steam under a relatively high pressure passing through a small break in the wall of a large bubble frictionally generates enough heat to cause ignition of the charge.

Thus, the prevention of the compression of bubbles in the bite of the rolls is a very desirable step in the differential rolling of smokeless powder as well as any other rolling operation where undesirable bubbles are likely to be formed.

An object of the present invention is to provide a method for rupturing protruding bubbles attaining a predetermined height in plastic composition during rolling to prevent such bubbles from entering the bite of the rolls.

Other objects of the invention will appear hereinafter, the novel features and combinations being set forth in the appended claims.

Generally described, the present invention comprises a method of rupturing and deflating protruding bubbles which are undesirably formed in a plastic sheet material and means for rupturing bubbles in said plastic sheet material.

A preferred embodiment of the invention has been chosen for purposes of illustration and description and is shown in the accompanying drawing forming a part of the specification, wherein reference symbols refer to like parts wherever they occur.

Fig. 1 is a front elevational view of a preferred form of apparatus for the embodiment of the invention.

Fig. 2 is a transverse sectional view of the ap-

2

paratus illustrated in Fig. 1 showing a plastic sheet being formed on one of the rolls of the apparatus.

Fig. 3 is an enlarged sectional view of a portion of the apparatus taken along line 3-3 of Fig. 1.

With reference to the drawing, a conventional type differential speed mill 10 with heated rolls has a high speed roll 11 adjacent to a low speed roll 12. A bar 13 is rigidly supported at each end by frame members of the mill 10. The bar 13 is superposed in juxtaposition to the high speed roll 11. The bar 13 is provided with sharp bubble rupturing projections or pins 14 at a predetermined distance from and at suitable increments along the face of the high speed roll 11. The pins 14, as shown in Fig. 3, are preferably formed of a shank 15 rigidly secured in the bar 13, a sharp point 16, and a sharp barb 17 adjacent to the point 16.

As illustrated in Fig. 2, during rolling of a wet charge 18, such as smokeless powder, bubbles 19 are formed as the moisture is rapidly evaporated from the charge being worked on the heated high speed roll 11. The charge 18 being formed into a plastic sheet is carried under the bar 13 in the direction indicated by arrow 20 and bubbles 19 protruding above the surface of said plastic sheet are ruptured by the pins 14 before entering the bite of the rolls. The rupturing of the bubbles 19 is greatly facilitated by the barbs 17 placed in a forward position as shown.

An example of the operation of the invention is given for the colloiding of a smokeless powder. The rolling mill utilized was of the type illustrated in the drawing and had the following characteristics:

Constant roll temperature ..... 105° C.
40 Gap between the rolls ..... .023 inch
Peripheral speed of faster roll ..... Approx. 113 ft.
per min.
Peripheral speed of slower roll ..... Approx. 95 ft.
per min.
45 Roll diameters ..... 14 inches
Roll lengths ..... 30 inches
The smokeless powder composition had the following formulation:

	Parts by weight
50 Nitrocellulose	49.50
Nitroglycerin	41.50
Ethyl centralite	9.00
Candelilla wax	0.08
55 The above composition, properly mixed in wa-	

ter, blended, dewatered and dried to a moisture content of approximately 13% by weight, was placed on the rolls of the mill in charges of predetermined weights suitable to the length of the rolls and size of sheet desired. The mill was provided with bubble rupturing means as illustrated in the drawing. Protruding bubbles, formed as the charge was worked on the faster roll, were efficiently and effectively ruptured by the pins set two inches apart and 0.4 inch above the faster roll.

In comparison with rolling operations not employing the bubble rupturing means, the frequency of fires was markedly reduced in the colloiding of smokeless powder when the bubble rupturing means was employed.

Differential rolling is not necessarily the limit of the practical application of the present invention. In this connection mention will be made of processes using equal speed rolls or a conveyor or table for progressing the plastic material where rupturing of bubbles is required.

Although barbed pins are used in the preferred embodiment of the invention, a plurality of knives, pins without barbs, circular cutters and the like similarly arranged over the plastic material may be mentioned among alternating bubble rupturing means.

It will be seen, therefore, that the advantages of the present invention reside particularly in the processing of hazardous plastic material, but that advantages also reside in any process where the bursting of protruding bubbles in a rolling

operation is required to improve the end product or the processing operation.

What I claim and desire to protect by Letters Patent is:

- 5 1. In the process of rolling an ignitable colloidable material, wherein protruding bubbles are undesirably formed and present a potential ignition hazard if compressed between the rolls, the improvement which comprises rupturing and deflating the bubbles reaching a predetermined height before entry into the bite of the rolls.
- 10 2. In the process of differential rolling smokeless powder wherein protruding bubbles are undesirably formed and present a potential ignition hazard if compressed between the rolls, the improvement which comprises rupturing and deflating the bubbles reaching a predetermined height before entry into the bite of the rolls.
